UNITED STATES PATENT OFFICE.

JOSE M. URBIETA, OF DEL RIO, TEXAS.

CAR-AXLE LUBRICATOR.

1,340,808.

Specification of Letters Patent. Patented May 18, 1920.

Application filed August 12, 1919. Serial No. 316,982.

To all whom it may concern:

Be it known that I, José M. Urbieta, a citizen of Mexico, residing at Del Rio, in the county of Val Verde and State of Texas, have invented certain new and useful Improvements in Car-Axle Lubricators, of which the following is a specification.

This invention relates to journal boxes for car axles of the type embodying means for positively feeding lubricant to the journal so as to prevent overheating. The invention aims to improve the adjunctive parts of the journal box so as to simplify the construction and enable access to be readily had to the interior of the journal box for replacement or other purpose.

The invention furthermore aims to prevent waste of lubricant and to insure an ample supply of the lubricant to prevent the wearing parts from becoming dry and also to exclude dust and foreign matter from the wearing parts and lubricant the box being closed and the journal protected so that dust is prevented from entering the oil reservoir and any surplus oil on the journal being disengaged therefrom and directed back into the reservoir to be again supplied by the oil feeding means.

The drawings illustrate a preferred embodiment of the invention. However, it is to be understood that in adapting the same to meet different conditions, various changes in the form, proportion, and minor details of construction may be resorted to without departing from the nature of the invention as claimed hereinafter.

The accompanying drawings illustrate an embodiment of the invention and on reference thereto;

Figure 1 is a vertical central longitudinal section of a journal box and wedge, provided with lubricating means illustrating the application of the invention, the reservoir shield and brass being shown in side elevation.

Fig. 2 is a vertical central longitudinal section of the parts shown in Fig. 1, the journal of the car axle being in elevation.

Fig. 3 is a top plan view of the oil reservoir and frame associated therewith for supporting the shield and the oil feeding means.

Fig. 4 is a longitudinal section on the line 4-4 of Fig. 3.

Fig. 5 is a sectional detail on the line 5-5 of Fig. 2, looking to the right, the dotted lines indicating the journal and the upper

portion of the shield and brass being broken away.

Fig. 6 is a view similar to Fig. 5 on the line 6-6 of Fig. 2, looking to the left as 60 indicated by the arrow.

Fig. 7 is a detail view of a portion of the oil reservoir and supporting spring, as seen from below.

Fig. 8 is a detail view of the combined closure and gage for the filling extension of the oil reservoir.

Fig. 9 is a detail perspective view of the spring for yieldably pressing the oil feeding roller against the journal.

Fig. 10 is a sectional detail of a portion of the frame and oil feeder support.

Fig. 11 is a sectional detail on the line 11-11 of Fig. 10.

Fig. 12 is a central longitudinal section of 75 the shield.

Fig. 13 is a transverse section on the line 13-13 of Fig. 12.

Fig. 14 is an end view of the shield.

Fig. 15 is a view similar to Fig. 12 of a 80 modification, in which the brass and shield are formed as one part.

Fig. 16 is a sectional detail on the line 16-16 of Fig. 15.

Corresponding and like parts are referred 85 to in the following description and indicated in the several views of the drawings by like reference characters.

The journal box 1 may be of any ordinary construction, such as commonly employed in 90 connection with car axle journals. The car axle journal 2 is mounted in the box 1 and the usual brass 3 and wedge 4 are mounted thereon in a manner well understood. A reservoir 5 is disposed within the lower portion of the journal box 1 and is supported upon a spring 6. Longitudinal ribs 7 are formed upon the under side of the reservoir 5 and have inwardly extending projections 8 at their outer ends which are adapted to 100 enter notches 9 formed in opposite edges of the spring 6. The ribs 7 are spaced apart a distance so as to receive the spring 6 between them and thereby prevent any lateral displacement of the spring, longitudinal displacement of the spring being prevented by the notches 9 and inner projections 8. The spring 6 is formed with an extension at its front end, in which an opening 10 is provided to receive a suitable instrument, 105 whereby to remove the spring when required. The reservoir 5 is adapted to re-

55

ceive a quantity of oil and is shallow and open at the top. An extension 11 is provided at the outer end of the reservoir 5 and is hollow and is designed as means to facilitate the filling of the reservoir when supplying oil thereto. The extension 11 projects upwardly a short distance in front of the journal 2 and its upper end is adapted to be closed by means of a cap 12. A projection 10 13 depends from the cap 12 and is of a length to extend into the filling extension 11 to within a short distance of the bottom of the reservoir. The projection 13 is provided upon one side with indicia to designate the quantity or level of the oil in the reservoir. The projection 13 within the indications thereon constitutes a gage. A connection 14, such as a chain constitutes connecting means between the projection 13 and 15 the reservoir 5 to prevent displacement or loss of the cap or closure 12. This is shown 20 most clearly in Fig. 2.

A frame is placed upon the reservoir 5 and comprises longitudinal members 15 and 25 transverse members 16. The longitudinal members 15 are formed with inner flanges or ribs 17 which touch the sides of the journal 2, so as to form a close joint therewith to remove surplus oil and prevent dust or 30 foreign matter from entering the reservoir. The lower edges of the longitudinal and transverse members of the frame have a rabbet connection with the upper edges of the sides and end portions of the reservoir 5, 35 whereby the frame is retained in place and a close joint between the parts assured. The inner flanges or ribs 17 incline in opposite directions from a medial point, as shown most clearly in Fig. 4 to direct the lubricant received thereon toward opposite ends 40 of the reservoir. Openings 18 are formed in the ends of the flanges or ribs 17 for the escape of the oil to the reservoir. The openings 18 flare toward their upper or receiving ends, as indicated most clearly at the 45 left in Fig. 4.

The oil feeding means comprise rollers 19 and 20. The roller 19 is disposed at the inner or rear end of the reservoir 5, whereas 50 the rollers 20 are located at the sides of the reservoir and intermediate the ends thereof. The roller 19 is disposed in an inclosed space 21 and its outer edge has a covering of rubber, leather or like material applied thereto. The inclosed space 21 connects by 55 means of an upwardly and outwardly inclined duct 22 with a trough formed at the inner edge of a flange 23 projecting from the rear end of the reservoir 5. Any oil 60 finding its way upon the flange 23 is directed by means of the duct 22 to the chamber 21 and is spread from the latter to the journal 2 by means of the roller 19.

Each of the rollers 20 is mounted in a support 65 24 which is pivotally connected to a

longitudinal bar 15 of the said frame. A pivot pin 25 passes through the upper end of each support 24 and through ears 26 formed upon the longitudinal members 15. A spring 27 is mounted upon the pin 25 by 70 means of ears 28 and opposite ends of the spring engage the frame and support so as to yieldably press the roller 20 against the journal 2. The spring 27 consists of a flat piece of spring material bent into the 75 form substantially as indicated in Fig. 9. The pin 25 is grooved at opposite ends to receive the ears 28 of the spring, whereby the pin is made secure when the parts are assembled. This is shown most clearly in 80 Fig. 11.

The brass 3 has extensions 29 at opposite sides to coat with the hanger, not shown, in a manner well understood. thereof and which enables the oil reservoir to be readily replenished when necessary, the quantity of oil in the reservoir being readily determined by means of the gage.

5 The foregoing description and the drawings have reference to what may be considered the preferred, or approved, form of my invention. It is to be understood that I may make such changes in construction and 10 arrangement and combination of parts, materials, dimensions, et cetera, as may prove expedient and fall within the scope of the appended claims.

Having thus fully described my invention, what I claim as new and desire to 15 secure by Letters Patent, is:—

1. In a car axle lubricator, an oil reservoir provided upon its bottom side with spaced longitudinal ribs having inner extensions at their outer ends and a supporting spring disposed between the ribs and having notches in opposite edges to receive the inner extensions of said ribs, whereby 20 to hold the spring from longitudinal or 25 lateral displacement.

2. In a car axle lubricator, an oil reservoir provided upon its bottom side with spaced longitudinal ribs having inner extensions at their outer ends and a supporting spring disposed between the ribs and having notches in opposite edges to receive the inner extensions of said ribs, whereby 30 to hold the spring from longitudinal or lateral displacement, said spring having an 35 extension at its forward end, in which an opening is formed for receiving a manipulating instrument.

3. In a car axle lubricator, an oil reservoir provided at its rear end with an 40 closed space and having a rearwardly ex-

tending flange and a duct connecting the inclosed space with the upper portion of the said flange and an oil feeding roller disposed in the inclosed space.

4. In a car axle lubricator, an oil reservoir, 45 a frame detachably mounted thereon and comprising longitudinal and transverse members, the transverse members being depressed and the longitudinal members having inwardly extending flanges which touch 50 the sides of the journal at their inner edges, said flanges sloping from a middle point toward opposite ends and having openings at opposite ends for the escape of lubricant into the reservoir.

5. In a car axle lubricator, an oil reservoir, 55 a frame detachably mounted thereon and comprising longitudinal and transverse members, the transverse members being depressed and the longitudinal members 60 having inwardly extending flanges which touch the sides of the journal at their inner edges and supports pivotally connected to the longitudinal members of the frame and provided with oil distributors.

6. In a car axle lubricator, an oil reservoir, 65 a frame detachably mounted upon the reservoir and having the lower edges of its side and end members connected with the upper edges of the sides and ends of the 70 reservoir by means of a rabbet joint and supports pivoted to the side members of the frame and provided with oil distributors.

In testimony whereof I affix my signature in presence of two witnesses.

JOSÉ M. URBIETA.
